J. E. FLOYD

LOCK

Filed Dec. 9, 1922

Inventor:
JOHN E. FLOYD

By *Tomie Rainey Hinkle*
attly

UNITED STATES PATENT OFFICE.

JOHN E. FLOYD, OF CHICAGO, ILLINOIS, ASSIGNOR OF ONE-HALF TO WELLINGTON S. WEMPLE, OF CHICAGO, ILLINOIS.

LOCK.

Application filed December 9, 1922. Serial No. 605,840.

To all whom it may concern:

Be it known that I, JOHN E. FLOYD, a citizen of the United States, residing at Chicago, in the county of Cook and State of Illinois, have invented certain new and useful Improvements in Locks, of which the following is a specification.

The invention relates to locks of the spring latch type.

One of the objects of the invention is to improve and simplify spring latches.

A further object is to provide means, operable by the key of the latch, to retain the bolt of the latch retracted so long as the key remains in the latch and to permit its movement by the spring of the latch when the key is withdrawn.

A further object is to improve and cheapen the construction of a standard door latch or night latch by removing two parts therefrom and arranging the remaining parts to perform additionally the function of the parts removed in a more convenient and practical manner.

Another object is to provide means which will yieldingly retain the key in the lock with the bolt retracted and which will not permit the key to be withdrawn until the bolt has first been released and moved to locked position.

Other objects and advantages will readily appear to persons skilled in the art from a consideration of the following description, when taken in conjunction with the drawing, wherein:

Fig. 1 is a section thru a door showing the key and lock mechanism with respect to the latch.

Fig. 2 is a plan view of the latch.

Fig. 3 is an enlarged view of the latch mechanism with the cover plate removed, showing parts in section taken on line 3-3 of Fig. 1.

Fig. 4 is a transverse section taken substantially on line 4-4 of Fig. 3.

In all of the views the same reference characters indicate corresponding parts.

Night latches, such as herein disclosed, are usually placed on doors provided with another lock and knob-actuated latch-bolt. To open the door, the knob-actuated latch-bolt must be withdrawn by rotating the knob, requiring the use of one hand, and the key-actuated latch-bolt must be withdrawn by rotating the key with the other hand, thus

requiring the use of both hands, as in each case the latch-bolt will be returned to normal locked position by the respective spring when released.

One of the important objects of this invention is the provision of key-operated means to hold the bolt of the night-latch retracted so that the same hand may be used to rotate the knob operated spring bolt.

Another important feature of the invention is the provision of similar means for holding the spring-bolt retracted by rotation of the knob of the night latch-bolt which is usually a part of the structure for operation on the inside of the room.

One form of the invention is embodied in the structure herein shown in which 5 is the casing of the latch and 6 is the cover plate held in place by the screw 7. A reciprocatable bolt 8 is provided with a tapered end portion 9 which normally projects thru an opening in the end plate 10 and is yieldingly held in this position by an open helical spring 11. The spring surrounds the shank 12 of the bolt 8.

The part 13 of the bolt forms a shoulder with the shank against which one end of the spring abuts. A plate 14 is provided with a central perforation thru which the shank 12 freely moves and serves as an abutment for the other end of the spring 11. The plate 14 is prevented from moving rearwardly by two projections 15 and 15', but it may be moved slightly forwardly by compressing the spring 11 to some extent.

When the bolt 8 is moved inwardly until the projection 9 is within the casing 5, as shown in broken lines in Fig. 3, the spring is compressed and will return the bolt to full line position when released.

Fastened to the rear end of the shank 12 of the bolt 8 is a cross bar 16. Two tumblers 17-17', one on each side of the bar, have aligning axes and are independently rotatable. The tumbler 17 is rotatable by a key operatable part 18 and the tumbler 17' is rotatable by the knob 19. When either tumbler is rotated less than one-half revolution in either direction, it will retract the bolt 8, as shown in broken lines in Fig. 3, and hold the bolt in retracted position, until it has been rotated slightly in the opposite direction.

The tumblers are substantially the same in form and each tumbler has ends 19-19'.

which engage the respective end of the bar 16 to move it rearwardly into broken line position (Fig. 3).

There are two projections 20—20' from the bar 14. When either end 19 or 19' of either tumbler 17—17', encounters the respective projection, the bar 15 is moved back against the spring 11 until the end has passed the projection, whereupon the bar 10 will be snapped back by the spring and the tumbler will be thus latched in position with the bolt retracted where it will remain until the tumbler engaged end has been manually moved in the opposite direction past the 15 aforesaid projection, after which the spring will move the bolt outwardly.

The key-operated tumbler 17 is secured to a sleeve 21 which has a slot 22 to receive a blade 18 that is rotatable by a key 23 for a 20 Yale lock 24 common in latches of this character.

The knob 19 has a stem 25 that is secured to the tumbler 17' by which the latter may be rotated.

25 The latch structure herein described is of standard type except for the projections 20—20' formed on the bar 14 and the absence of the two parts commonly used to hold the bolt retracted when moved to re- 30 tracted position by the knob 19.

While I have herein shown and described only a single embodiment of my invention,

it is manifest that changes may be made in the form of structure within the spirit and scope of the appended claims.

Having described my invention what I claim as new and desire to secure by Letters Patent, is:—

1. A latch structure having a reciprocatable spring-pressed bolt; a cross-bar secured to the rear end of the bolt; a rotatable tumbler having two ends selectively to engage the bar when rotated to retract the bolt, and a spring-pressed latch-member to engage the other end of the tumbler to yieldingly hold the bolt retracted against the spring.

2. A latch structure having a reciprocatable bolt; a spring yieldingly holding the bolt extended; a plate movable axially of the bolt affording one abutment for the spring; a cross-bar secured to the inner end of the bolt, in rear of the plate; a rotatable tumbler having two ends normally bearing against the bar selectively to retract the bolt when rotated and a latch-member on the plate to engage the other end of the tumbler to hold the bolt in retracted position and which will disengage the tumbler when the latter is forcibly moved in opposite direction.

In testimony whereof I hereunto subscribe my name.

JOHN E. FLOYD.
